UNITED STATES PATENTS

1,031,468 7/1912 Power ..... 83/156 X

ABSTRACT: A paper punch with adjustable and depressable paper stop means is described having a novel construction of means operating for the cutting punches by cams. In addition a single cam depresses the paper stop out of the way and also brings a feed roll into contact with the punches sheets for ejecting the same under the cutting punches. The paper stop is adjustable with respect to the cutting punches whereby the location of the punched holes with respect to the edge of the sheets may be adjusted without affecting the means for depressing the paper stop means or the timing thereof.

PAPER PUNCH

The paper punch is designed primarily for punching holes adjacent to the edge of a pile of sheets of paper which holes receives a fastening device although the construction of punch is applicable to other sheets provided there is sufficient power.

It is an object of the invention to construct a paper punch having paper stop means using stops which are depressed below the table top by cam means so that the punched sheets can be ejected straight through the paper punch towards the back and under the cutting punches.

Another object is to construct a simple and new connection with the punch bar which drives the cutting punches through the pile of sheets.

In addition, it is an object to construct a paper stop means that can be adjusted relatively to the cutting punches thereby enabling the distance of the holes from the edge of the pile of sheets to be selected as desired without effecting any other function of the punch.

Another object is to provide a cam for depressing the paper stop means and using the same cam to elevate an ejecting roller into contact with the pile of sheets so that a fixed time relation is unalterably maintained between the depression of the stop means and the engagement of the ejecting roller with the pile of punched sheets to be ejected.

Other objects of the invention will be more apparent from the following description when taken in connection with the accompanying drawings illustrating a preferred embodiment thereof in which:

FIG. 1 is a front view of the punch with portions removed and in section for clarity;

FIG. 2 is an end view of the punch and partially in section as taken on line 2-2 of FIG. 1;

FIG. 3 is a sectional view taken on line 3-3 of FIG. 1;

FIG. 4 is a partial rear view as seen from line 4-4 of FIG. 3 with the clutch in section;

FIG. 5 is an enlarged view of the clutch solenoid and its clutch operating means;

FIG. 6 is a view of a clutch element;

FIG. 7 is an enlarged detail of the stop means; and

FIG. 8 shows a nonrepeat circuit.

The paper punch includes a frame of suitable form, that shown including a pair of spaced sideplates 10 which are retained in spaced relation by a pair of crossbars 11 which are secured to the plates by bolts 12. The frame also includes a top plate 13 which is secured to the crossbars by bolts 14. Supporting plates 15 are part of the frame located between the sideplates and secured in spaced relation thereto such as by sleeves 16 and bolts 17. A secondary supporting plate and gear casing 18 is secured to the one of the first supporting plates by suitable spacers 19 and nuts 20. A table 21 is secured to the sideplates by bolts 22.

The paper punch includes a main shaft 24 having a belt pulley 25 mounted thereon to be belt driven by a suitable motor. Preferably the main shaft has fly wheels 26 at each end thereof for smoothing out the power delivered to the cutting punches. The drive shaft carries a pinion 27 secured to the drive shaft which meshes with a gear 28 carried by a jack shaft 29 mounted in the supporting plates in bearings. The jack shaft is connected through a pinion 30 to a gear 31 normally freely rotatable on a camshaft 32 and held against axial movement by a retaining ring 33.

A punch bar 36 is mounted for reciprocation in slots 37, FIG. 1 provided in the sidewalls. A selector pin frame formed by a spaced flange means 38 is secured to the punch bar by bolts 39. The selector pin frame carries a series of selector pins 40 slidably mounted in the flange means, each selector pin carries a punch connecting portion 41 at the end thereof which is movable into a position between the punch bar and its cutting punch and to a position away therefrom when it is desired that one or more of the cutting punches be rendered inoperative. The connecting portion is rectangular or square so that it is retained against turning by a flat thereof engaging

the bottom of the punch bar. A spring 42 engaging in a retaining notch 43 in the selector pin retains the connecting portion of the selector pin in operative position spaced from the end of the cutting punch or in a like adjacent notch to retain the same in a position spaced from alignment with the punch bar or in inoperative position.

Each cutter or cutting punch 48 is mounted for reciprocation in a cutting punch frame formed by a pair of punch plates 49 secured by a bolt 50 to a punch support bar 51 which is attached to end brackets 52 by bolts 53 and this bar is secured to the end of the top plate 13 by bolts 54. An anvil 55 cooperates with the cutting punches and is secured to the top plate 13. A stripper plate 56 is also secured to the punch support bar which also serves as a guide plate for the pile of sheets projected into the slot formed between this plate and the table and anvil. Each cutting punch also carries a withdrawal projection 57 at the upper end thereof which is engaged by an angular withdrawing plate 58 which is secured to the punch bar 36 by a screw 59.

Operating means is connected with the punch bar 36 to reciprocate the same and the cutting punches. This operating means show includes cam means secured to the camshaft 32 and includes two sets of cam means one on each side of the punch frame. Any suitable cam means may be used, however, that illustrated includes a punching cam 63 which applies the downward or punching stroke to the cam bar and a retracting cam 64 for retracting or raising the cam bar. Each cam means operates a cam lever 65 comprising two spaced plates which 20 cam lever is pivotally mounted on the frame on a pivot 66. The cam lever carries a cam follower 67 between the plates which engages the punching cam and it also carries a cam follower 68 outside of one plate which is engaged by the retracting cam 64. Arms 69 are attached at one thereof to each cam lever by 25 an arm pivot 70 which is spaced from the cam lever pivot far enough to provide a punch stroke of sufficient distance to carry past the anvil. The other end of each arm is secured to the punch bar 36 such as by arm openings 71 which receive the bar. Spring means 72 may be attached to the punch bar to assist in retracting the bar and the cutting punches.

The camshaft 32 is connected with the drive gear 31 by a one revolution clutch, FIG. 4. This clutch includes a collar 76 secured to the camshaft 76 by a key 77 and has splines 78 which engage cooperating splines 79 on a clutch element 80 which is slidably axially on the camshaft. The clutch element has clutch teeth 81 at the end thereof adapted to engage with cooperating clutch teeth 82 on the hub of the drive gear 31. A clutch spring 83 normally presses the clutch element to slide the same axially on the clutch shaft to bring the clutch teeth 81, 82 into driving engagement. A clutch release cam 84, FIG. 6, is secured to the clutch element by screws 85. A clutch operating element or roll 86 is carried by a clutch lever 87 and engages the clutch cam to hold the clutch teeth disengaged against the pressure of the spring 83. The lever is pivotally mounted on a pivot 88 and is operated by a solenoid 89, having a connecting link 90. The solenoid is carried by the second supporting plate 18.

Energizing of the solenoid raises the clutch roll 86 radially away from the clutch cam and clutch element so that the clutch spring 83 propels the clutch element axially to engage the clutch teeth 81, 82, and establish a driving connection between the drive gear 31 and the camshaft. A spring 91 connected with the clutch lever propels the clutch operating element or roll 86 inwardly into the path of the clutch cam upon deenergization of the solenoid. Near the end of one revolution of the clutch element, clutch cam 84 engages the roll 86 to press the clutch element to the right as viewed in FIG. 4 and disengage the clutch teeth and terminate rotation of the clutch shaft on one revolution thereof.

A manual switch 94 energizes the solenoid 89. A nonrepeat means, FIG. 8, prevents repeat operation should the switch 94 be held depressed. This means includes a normally open switch 95 mounted on the frame to be engaged and closed by 75 the punching cam 63. A relay 96 has contacts 97, 98 in series

with the solenoid and which are normally closed. Switch 95 is connected in series with the relay 96 so that the latter is energized when switch 95 is closed to open the connection with contact 98 and close the connection with contact 99. If switch 94 is held depressed, relay 96 remains energized to hold contacts 97, 98 open.

The paper punch has stop means for locating the edge of the pile of sheets the desired distance from the cutting punches. The stop means includes a plurality of stop bars 100 slidably mounted in a stop bar frame 101 for retraction of the stop bars below the anvil. The stop bar frame extends substantially across the paper punch and constitutes a plate having its longitudinal edges bent around to parallel the plate but spaced therefrom a distance corresponding to the thickness of the stop bars. A notch cut through the top and bottom edge for each slide bar provides a passage therefor. A spring 102 for each stop bar normally projects the same upwardly in a slot in the top plate 13 and anvil 55 with their ends abutting the stripper plate 56.

Stop actuating means is provided to depress the stop means in timed relation with the termination of the punching operating and the cutting punches have been raised to initial position. This stop actuating means includes a stop cam 105, FIG. 2, secured to the camshaft so that it is in timed relation with the operating cam means 63, 64 for the cutting punches. The stop cam engages a stop cam follower 106 carried by a stop lever 107 which is pivotally mounted on the frame on a pivot 104 carried by the supporting plates 15 of the frame. This lever has a link 108 attached thereto by a pivot 109 and the other end of the link is attached by a pivot 110 to a secondary lever 111 which is pivotally mounted on the frame to a pivot 112. The secondary lever has a secondary connecting link 113 pivotally mounted on a pivot 114 on the secondary lever and the other end of this link is pivotally attached by a pivot 116, FIG. 7, to a retracting frame 115 which is pivotally mounted on a pivot 117 to a bracket 118 secured to the stop frame 115. The retracting frame 115 carries a flange engaging a flange on each stop means 100. The retracting frame depresses the stop means and the spring 102 for each stop means raises the same to stop position. A spring 119 attached to the lever 107 retains the retracting frame raised and the cam follower 106 in contact with the cam 105.

When the backstop cam 105 rotates and propels the stop cam lever 107 in a clockwise direction as viewed in FIG. 2, the link 108 is pressed downwardly to press the secondary lever 111 downwardly. This pulls the secondary link 113 downwardly and pivots the stop frame 115 downwardly to pull all of the stop bars 100 down below the level of the anvil or table top. The pile of sheets which has been punched is then projected beneath the cutting punches to the back of the punch where it may be deposited in a suitable table (not shown).

Preferably, the stop means and hence the stop bars 100, FIGS. 2 and 7, are adjustable towards and away from the cutting punches so that the holes in the punched sheets may be located at any desired distance from the edge. A slot in the anvil and top plate is provided to allow for this adjustment. Means are provided for adjusting the position of the stop means which includes a pair of spaced stop rods 123 to which the stop frame 115 is secured such as by a collar 124 welded to this frame and a clamping screw 125. The stop mounting rods are mounted for longitudinal movement in holes in the frame or particularly in the frame crossbars 11. One end of one of each of these rods is attached to a pin 126 on an adjusting lever 127 which is mounted on a shaft 128 pivotally mounted on the frame. This shaft is secured to an indicator lever 129 having a scale 130 to indicate the position of the stop means. By adjusting the position of the stop means the distance of the punched holes from the edge of the pile of sheets can be adjusted as desired over the range of the adjustment. The indicator lever has a slot in which is received a lock screw 131 for securing the indicator lever and the stop means in adjusted position. The secondary link 113 is made long enough so that it accommodates for all adjusted positions of the stop means.

Ejecting means is provided to eject the pile of punched sheets underneath the cutting punches after the stop means has been depressed out of the way. This means includes a rotatable ejecting roll 135 carried on a roll frame 136 having spaced arms which arms are secured to a shaft 137. The ejecting roll has a sprocket 138, FIG. 3, secured thereto. A chain 139 between this sprocket and a second sprocket 140, which is freely rotatable on the shaft 137 provides a driving connection therebetween. A third sprocket 141, FIG. 1, is suitably secured to the second sprocket and receives a chain 142 going to a sprocket 143 carried by the drive shaft 24. By this drive connection, the ejecting roll is constantly rotating but it is normally below the table 21 and not in contact with a pile of sheets, as illustrated in FIG. 3.

The ejecting roll is raised into contact with the bottom sheet of the pile of sheets preferably by the same cam 105 which depresses the stop means so that the two are at all times accurately timed together, that is, the stop means has been depressed before the ejecting roll is raised into contact with the pile of sheets. Preferably, too, this connection includes a lifting arm 147 on the stop cam lever 107 which carries a pull link 148 mounted on a pivot 149. This pull link has a slot 150 which receives a pin 151 carried by a lift lever 152 which is secured to the shaft 137 carrying the arms 136 forming the ejecting roll frame. The ejecting roll is well below the table so that when the stop means cam 105 pivots the stop lever and lift arm 147, the ejecting roll is still below the table until the stop bars 100 have been fully depressed. Continued pivoting of the lift arm 147 raises the ejecting roll 135 into contact with the pile of sheets which are pressed against a freely rotatable idler roll 153 which is rotatably mounted on a shaft 154 above the table. The rotating ejecting roll projects the pile of sheets underneath the cutting punches to the back of the punch. A spring 155 flexibly presses the ejecting roll against the pile of sheets and also accommodates for the varying number of sheets.

It is desirable that each pile of sheets be separated from each of the other piles of sheets. This may be accomplished by a known pile receiving table (not shown) which is shifted to and from two angular positions by means driven from the cam shaft. This shift means is shown, FIG. 1, as a gear 158 secured to the camshaft 32 and meshing with a gear 159 carried on the frame and providing a 1 to 2 gear ratio. The gear 159 has a crank or link 160 mounted on a pin 163 spaced from the center of the gear which rocks a lever 162 which is pivotally mounted on a spacer 161. This lever is connected with a receiving table by a link 164 to shift the table to and from each angular position for each two revolutions of the camshaft.

This invention is presented to fill a need for improvements in a paper punch. It is understood that various modifications in structure, as well as changes in mode of operation, assembly and manner of use, may and often do occur to those skilled in the art, especially after benefiting from the teachings of an invention. This disclosure illustrates the preferred means of embodying the invention in useful form.

What I claim is:

1. A paper punch comprising a frame having a table, a drive shaft, an anvil, a punch bar mounted on the frame for reciprocation towards and away from the anvil, a plurality of cutting punches, mounting means mounting the plurality of cutting punches in alignment with the punch bar so as to be engaged thereby, the anvil cooperating with the cutting punches; operating means connected with the punch bar to reciprocate the same in one direction towards the anvil for punching and then retract the same to initial position including operating cam means, a camshaft carrying the cam means, and clutch means to connect the camshaft with the drive shaft and disconnect the same on one revolution of the operating cam means, the operating cam means providing a dwell for the operating means after the return of the punch bar and cutting punches to initial position; stop means including stop bars and mounting means mounting the stop bars adjacent to the cutting punches and for movement from stop position to a position below the anvil and return, ejecting means including a

roll frame and an ejecting roll carried thereby and driven from a drive shaft, the roll frame being movably mounted to raise the roll into contact with the pile of punched sheets and eject the pile under the cutting punches to the back of the punch, and actuating means connected with the stop bars to retract and return the same and connected with the ejecting means to bring the ejecting roll into contact with the pile of sheets after the stop bars have been retracted.

2. A paper punch as in claim 1 in which the actuating means is a single actuating cam carried by the camshaft.

3. A paper punch as in claim 2 in which the connection between the actuating cam and the ejecting roll frame is a cam lever, and the connection between the cam lever and the roll frame includes a spring to resiliently pull the ejecting roll above the table into contact with a pile of sheets.

4. A paper punch as in claim 1 in which the operating means for the punch bar includes an operating lever mounted on the frame on a pivot including a pair of spaced plates, arm means connecting the operating lever with the punch bar at a point spaced from the pivot, the cam means including a drive cam between the spaced plates of the operating lever and a retracting cam, a first cam follower carried by the operating lever and engaged by the drive cam to drive the punch bar and cutting punches downwardly and a second cam follower spaced angularly from the first cam follower and engaged by the retracting cam to retract the punch bar upwardly to initial position.

5. A paper punch as in claim 4 including a solenoid connected with the clutch means to release the same, spring means to engage the clutch means, a normally closed operating switch connected with the solenoid, a normally closed relay switch in series with the solenoid circuit, and nonrepeat means connected with the normally closed relay switch including a relay to open the same and the relay remaining energized so long as the operating switch is held closed.

6. A paper punch as in claim 1 in which the stop actuating

means includes a stop cam lever operated by the stop cam means, the ejecting roll frame being pivotally mounted on the main frame and normally retaining the ejecting roll below the table far enough so that the ejecting roll is brought into contact with the bottom of the pile of sheets after the backstop means has been retracted.

7. A paper punch as in claim 1 in which the mounting means for the stop bars is mounted for movement towards and away from the cutting punches, and the stop retracting means engaging the stop bars in all adjusted positions.

10 8. A paper punch as in claim 7 in which the mounting means for the stop bars is adjustably mounted to adjust the stop bars towards and away from the cutting punches, and in which the retracting means for the stop bars includes a retracting frame pivotally mounted on the mounting means, and a connecting link connected with the retracting frame of substantial length to accommodate for the adjusted positions of the mounting means.

15 9. A paper punch as in claim 1 in which the clutch means includes a clutch element slidably mounted on the clutch shaft, a clutch release cam carried by the clutch element, a clutch lever having a clutch operating element carried thereby, a pivot pivotally mounting the clutch lever to move the clutch operating element radially away from the clutch release cam and radially inwardly to return the same into the path of the clutch cam and shift the clutch element to release the same.

20 10. A paper punch as in claim 1 including selector pins for each cutting punch having a rectangular connecting portion providing flat surfaces, selector pin mounting means mounting the selector pins with a flat surface of the connecting portion engaging the bottom of the punch bar to retain the pins against turning, and the selector pin mounting means mounting the selector pins for movement to and from a position in alignment with the cutting punches.
